UNITED STATES PATENT OFFICE.

ELMER Z. BURNS, OF MADISON, NEW JERSEY, ASSIGNOR TO THERMOGEN EQUIPMENT COMPANY, INC., A CORPORATION OF NEW YORK.

AUTOMATIC DRAFT CONTROLLER.

Application filed August 3, 1923. Serial No. 655,529.

To all whom it may concern:

Be it known that I, ELMER Z. BURNS, a citizen of the United States, residing in Madison, Morris County, State of New Jersey, have invented certain new and useful Improvements in Automatic Draft Controllers, of which the following is a specification.

The present invention has relation to certain improvements in the construction and arrangement of automatic draft controlling apparatus of the type described and claimed in United States Patent to Burns and Keiller, Number 1,433,446 dated October 24th, 1922. The objects and advantages of the improvements forming the subject matter hereof will be set forth in connection with the description of said improvements in this specification.

These improvements are illustrated in the accompanying drawings wherein Figure 1 is a front elevation of a complete machine embodying the improvements herein claimed, Figure 2 is a diagram of the electrical connections, Figures 3 and 4 are side elevations of one of the three point switches in the on and off positions respectively, Figure 5 is a rear view of one of these switches, Figure 6 is a top view of the same, Figure 7 is a front elevation of the main switch lever, Figure 8 is a longitudinal sectional view of the same, Figure 9 is a front elevation of the row of primary circuit closers for the motor, Figure 10 is a top view of the same, Figure 11 is a cross sectional view of the same on the line 11-11 in Figure 9, and Figure 12 is a side elevation of the side bracket on the main frame, showing the preferred mode of mounting the damper-actuating levers thereon.

In Figure 1, the main frame is shown at 10, and attached at one side thereof is the bracket 11 upon which is mounted a revolute shaft 12. At 13 is shown a portion of the lever intended to operate the damper or other draft regulator, which may be of any well known character as stated in said patent to Burns and Keiller. This lever 13 is fixed to the shaft 12, and the shaft can be revolved for operation of the damper or its equivalent, by means of a second lever 14, preferably slotted at its upper extremity as shown at 15.

As in said Burns and Keiller patent, the "impelling means" proper preferably takes

the form of a threaded bar 16, mounted for longitudinal movement, and driven back or forth by a worm wheel 17 driven by the reversible electric motor 18. The end of this impelling bar 16 carries a pin 19 which passes through the slot 15 on the lever 14, and serves to transmit motion to said lever. The impelling bar 16 corresponds to the like element shown at 12 in the Burns and Keiller patent, and is mounted and made to move as therein described. This bar carries a roller 20 corresponding to the roller 81 in the Burns and Keiller patent.

The main switch lever 21 is pivoted at 22 and corresponds functionally with the lever 25 of the Burns and Keiller patent. At its lower end it is provided with a curved sector 23, carrying pins 24, which operate the reversing switch shown at A in Figure 2, all in a manner fully described in the Burns and Keiller patent.

The means whereby changes in steam pressure produce movements of the lever 21 comprise the pressure piston 25, the main pressure balance arm 26, and accessory devices, all as found in the Burns and Keiller patent. Figures 7 and 8 show the preferred means whereby small movements of the balance arm 26 are made to produce a relatively wide swinging movement of the lever 21. These means comprise a slender connecting bar 27 pivotally connected at 28 with the balance arm 26 and similarly connected with an offset from the lever 21 very close the fulcrum 22, as shown at 29. The upper end of the lever 21 carries the roller 30 which operates the primary circuit closing switches in the following manner.

In Figures 1, 9 and 10, five of these primary circuit closing switches are shown, corresponding to the switches 49 in the Burns and Keiller patent. These switches are carried on an insulating base 31, and preferably comprise two normally separated and mutually insulated springs 32, 33, carrying spark-resisting points 34, 35 at their free extremities. The spring 32 of each switch carries a projection 36 passing upward through a curved track 37 over which rolls the roller 30 on the lever 21. It will be clear that, as the roller 30 moves over the track 37 (struck on an arc whose center is the fulcrum 22 of the lever 21) this roller will depress the upper spring 32 of each of the circuit closing switches in turn, there-

by bringing the points 34 and 35 together and closing circuit at each switch in turn as hereinafter described.

At B in Figure 1 is shown a row of 5 circuit preserving relay magnets corresponding to those shown at 50 in the Burns and Keiller patent. The connections for these are shown in Figure 2.

Figures 3, 4, 5 and 6 show the details 10 of the improved three-point switch which I have substituted for the two point circuit-breaking switches 73 to 79 of the Burns and Keiller patent. An important difference between the arrangement of these 15 switches as compared with those of the Burns and Keiller patent is that in the present construction all the switches are normally connected in series with each other, while in the Burns and Keiller patent each 20 switch is independent of the others. The advantage of this change will appear hereinafter.

In the present construction, as in that 25 of Burns and Keiller, the circuit-breaking switches are mounted on a bar 38, parallel to the impelling bar 16; and these switches are made adjustable as to their relative 30 positions, being slidable along their support. The reasons for this adjustability are fully described in the Burns and Keiller patent. For this purpose, each switch comprises a frame 39 held adjustably on the bar 38 by a clamping plate 40 and screws 41.

The series circuit through these switches 35 is maintained through two side contact pieces, 42 and 43, on the upright part of each frame 39. These side contact plates have extensions curving around to the back 40 of the frame 38 and making contact with successive sections of the series wire 44, as plainly shown in Figures 3, 4 and 5.

The "branch contact" of each switch 45 preferably comprises leaf springs 45 fixed on the top of the frame 38, and connected permanently each with a wire leading to a separate circuit-closing switch (see Figure 2).

The movable contact of each switch is 50 preferably a bent metal plate 46, the top of which is furnished with an extension 47, which is closely embraced by the springs 45, when the plate 46 is in its upper position (Figure 3). In this position, the side 55 lips 48 make contact on opposite sides with the series contacts 42 and 43 (best shown in Figure 6). Consequently in its upper position, where it is held by the friction of the contacts 42 and 43, the plate 46 acts to place all three fixed contacts 42, 43 and 45 in electric connection. When in lower 60 position, however, the three contacts are all isolated from each other (see Figure 4).

The up and down movement of the movable switch member 46 is preferably accomplished as follows. A plate 49, fixed

on the switch frame serves as a guide for an arm 50 fixed on a slidably plunger 51 carrying a roller or wheel 52, and passing down through the bottom of the frame. A spring 53, attached to the arm 50, tends 70 to pull it and the plunger 51 downward. A swinging hammer 54 is pivotally supported at one end in ears 55 on the arm 50, and a spiral spring 56 has one end fixed to the plate 49 and the other to the free extremity of the hammer 54. The scope of movement of the plunger 51, arm 50 and ears 55 is such that at the top and bottom of their travel the fulcrum of the hammer 54 is on opposite sides of the point of attachment of the spring 56 to the plate 49. (See Figures 3 and 4.)

The result of this construction is that, when the plunger 51 is lifted, the hammer 54 is swung rapidly and suddenly upward 85 so as to strike the upper horizontal portion of the plate 46, which throws said plate into the closed circuit position shown in Figure 3. Opposite movement of the plunger causes a similar quick downward blow on the plate 46, which opens circuit, as in Figure 4. As shown in Figure 1 the roller 20 on the impelling bar 16 travels along under these switches and raises the 90 plungers 51 singly in succession. As soon as the roller passes a switch, the circuit there made is broken by the falling of the 95 plunger 51, caused by the tension of the spring 53.

Bearing in mind the correspondence of 100 the various parts above described with the parts of the Burns and Keiller device aforementioned, it will now be easy to understand the mode of operation of the entire device, which I shall now describe with 105 particular reference to Figures 1 and 2.

The row of circuit making switches is 110 shown in Figure 2 having the form indicated in the Burns and Keiller patent, and it is to be understood that such switches may be used in the present connection, but the 115 form of switch already described with reference to Figures 9, 10 and 11 is preferred. Whichever form is used it will be understood that a temporary closure of circuit is effected at each switch in succession, as the end of the main lever 21 passes such switch.

Any reversible motor 18 may be used to 120 operate the impelling bar 16 to move the damper or equivalent device. In Figure 2 is indicated diagrammatically a motor having a series field magnet coil 57 and a shunt coil 58. The armature is indicated at 59.

Assuming that there has been a fall of 125 pressure which has caused the lever 21 to tilt anti-clockwise in Figure 2, closing circuit in the middle switch of the series as it passes the same, as indicated in Figure 2. Current will then enter on the main wire 130

and flow as follows—partly through the shunt coil 58, directly to the outgoing wire 61—the remainder through the series field magnet coil 57 wire 62 to reversing switch

5 A, magnet coil 63, wire 44, circuit-breaker 64, wire 65 to the middle circuit closing switch 66, wire 67 to relay primary 68, wire 69, resistance 70, wire 71, armature 59, wire 72 to reversing switch A and thence to the

10 outgoing wire 61.

This at once starts the motor 18 so as to move the impelling rod and the roller 20 to the right in Figure 2. This may be assumed to open the damper or otherwise cause

15 increase of draft to compensate for the drop in pressure. At the same time the relay 68 closes the switch at 73 to maintain closure of the motor driving circuit, in a manner described in the Burns and Keiller patent.

20 Assuming that the lever 21 does not close any other switch, the motor 18 will be brought to rest as soon as the roller 20 reaches the circuit-breaker 64, as is made clear from the Burns and Keiller patent.

25 All the description of operation of the Burns and Keiller circuit-breakers and their relation to the movements of the main switch lever and circuit-closers operated thereby applies to the present construction, save that

30 the three point switches herein described connected as shown with the series wire 44 is novel, and makes it necessary for the current to pass through all the switches on one side of that which is connected to the particular circuit closer which has last operated. This is the opposite side to the corresponding position of the roller 20.

35 The object of this improvement is to prevent a possible driving of the impelling device all the way to the limit under certain accidental conditions when this would not be desirable.

40 In the form shown in Burns and Keiller, wherein each circuit-breaker is in a branch independent of all the others, it is conceivable that the lever 21 (numbered 25 in Burns and Keiller) might be impelled to left and then to right in quick succession by a surge of steam pressure, and this might occur in

45 such a position as to operate one and the

same circuit closer a second time and continue its second swing far enough to operate another circuit-closer, before the roller 20 (or 81 in Burns and Keiller) had reached the first circuit-breaker in its path. The 55 result of this would be that circuit would be closed through a circuit breaker behind the moving roller on the impelling bar. Obviously, under these conditions there would be nothing to stop the impelling bar until the roller reached one of the limit switches, shown at 73 and 79 in the Burns and Keiller patent.

60 By using the series connection shown herein, if the roller 20 failed to open circuit at 64 (when moving toward the right in Figure 2) it would certainly open circuit at the next switch to the right. I have shown limiting two-point switches at 74 and 75 in Figure 2, but they are not strictly necessary 70 in this arrangement.

65 Various changes may be made in the construction and arrangement of this apparatus without departing from the scope of my invention which is not limited to the details 75 herein shown and described.

What I claim is—

1. In an automatic draft controlling apparatus driven by an electric motor, a succession of circuit breakers each provided 80 with a reciprocating plunger adapted to operate it, electrical connections normally connecting said circuit breakers in series with said motor, and automatic means for operating said circuit breakers successively, 85 said means comprising a roller adapted to travel along the series of plungers so as to cause operative movement of one plunger at a time.

2. In an automatic draft controlling apparatus driven by an electric motor, a succession of circuit-closing switches, each comprising a depressible spring, and a main switch lever pivotally mounted and having a roller adapted to travel along said succession of circuit-closers so as to depress said springs one at a time in succession. 95

90 In testimony whereof I have hereto set my hand on this 1st day of August, 1923.

ELMER Z. BURNS.
